HEEL AND METHOD OF ATTACHING

James Cavanagh, Cohasset, Mass., assignor to
 United Shoe Machinery Corporation, Paterson,
 N. J., a corporation of New Jersey

Application September 12, 1934, Serial No. 743,663

7 Claims. (Cl. 36—34)

This invention relates to shoe heels and is particularly concerned with the provision, as an article of manufacture, of a prepared, loaded heel which is ready for immediate attachment to a shoe without the necessity of driving nails, screws or other metallic fastenings.

It is an object of the invention to provide a superior heel which can be manufactured and sold to shoe manufacturers and repairers in competition with the ordinary wood and leather heels of commerce and which will offer advantages in respect to both ease and security of attachment to the shoe to which it is applied.

In the illustrative embodiments of the invention disclosed herein, the above-stated object is realized by the provision of a heel which has permanently embedded therein and projecting from the attaching face thereof heel attaching fastenings made of some stiff, strong material which is capable of being readily softened to a condition of easy deformability. According to the nature of the material employed for the fastenings, the softening of them to permit them to be upset or clinched in the shoe to which the heel is to be attached may be effected either by the application of a solvent or by the application of heat. The material selected for the fastenings may be celluloid, which is both thermoplastic and capable of being softened by various solvents, or it may be cellulose acetate or some other cellulose derivative composition having one or both of these characteristics; or it may be any one of many thermoplastic and/or soluble resins of which an example is vinyl resin.

Although a number of materials have been suggested in the preceding paragraph in order to provide an adequate disclosure of the invention and to facilitate an understanding thereof, the invention is not limited to the use of the particular materials mentioned but embraces the use of other materials which are equivalent in respect to being capable of being readily softened to a condition in which the fastenings can be upset, flattened, clinched or otherwise so deformed as to provide a secure attachment of the heel to the shoe.

In one desirable embodiment of the invention, the heel is molded to the desired shape from a plastic composition containing wood or leather, the fasteners, for example of celluloid, being molded directly into the heel and projecting from the attaching face thereof. Such a heel is light, strong, easily attached without metallic fastenings, and perfectly adapted for covering or other

finishing in the manner in which wood heels are commercially covered or finished.

If preferred, the fasteners may be embedded in the heel by drilling holes all the way through the heel and pushing the fasteners through from the tread end of the heel until they project the desired distance from the attaching face. If headed fasteners are employed, their heads may be sunken in recesses counterbored in the heel so that they will not interfere with the subsequent attachment of a toplift. The fasteners may be thus applied to any kind of heel, whether of wood molded composition or leather.

Still other ways of embedding fasteners in a heel embodying my invention may be employed with advantage under some circumstances. For example, I contemplate drilling holes through the attaching face to a sufficient depth in the heel, introducing pyroxylin solution or cement into the holes and then forcing celluloid rods into the cement, leaving a suitable length of each rod projecting from the attaching face of the heel. In this connection, it may be advantageous to screw thread or otherwise cut into the walls of the holes to provide great strength of cement attachment of the rods to the heel.

The invention further includes a novel method of attaching a heel to a shoe by loading the heel with a plurality of stiff fasteners, preferably of pyroxylin, leaving the ends of the fasteners projecting from the attaching face of the heel, making a plurality of holes through the heel seat of the shoe, passing the projecting ends of the fasteners through the holes, softening the ends of the fasteners and flattening them or bending them outward upon the insole inside of the shoe. By the practice of my improved method, a heel may be attached very simply and rapidly and with such exceptional security that there is no possibility of detaching it without destroying the shoe.

The foregoing and other features and advantages of the invention will be better understood from reading the following detailed description of several embodiments thereof in connection with the accompanying drawing, in which

Fig. 1 is a perspective view of a molded heel embodying the invention, with a portion broken out to reveal the internal structure;

Fig. 2 is a view of the heel portion of a shoe, partly in longitudinal section and partly in elevation, showing the heel attached thereto;

Fig. 3 is a sectional view of a leather or other built-up heel embodying the invention;

Fig. 4 is a sectional view upon the line IV—IV 55

of Fig. 5, showing a modified form of the invention, illustrating also its application to the attachment of a toplift to a heel;

Fig. 5 is a perspective view showing the tread face of the heel shown in Fig. 4; and

Fig. 6 is a sectional view illustrating another modified form of the invention.

Referring now to Figs. 1 and 2, 10 indicates a heel which may be molded to the desired size and 10 form from a plastic composition containing wood, leather or other material suitable for the production of a heel having the qualities desired. In the operation of molding the heel, there will 15 preferably be permanently embedded therein a plurality of fasteners 12 of a normally stiff, strong material which is capable of being readily softened to a condition of easy deformability, the ends of such fasteners being left projecting a considerable distance from the attaching face of the heel as 20 illustrated in Fig. 1 and the fasteners preferably having enlarged heads, as shown at 14, securely embedded in the composition from which the heel is molded.

An excellent material for the fasteners 12 is 25 celluloid or other equivalent pyroxylin composition which is capable of being readily softened by the application of any one of several well-known solvents, or even by heat. It should be understood, however, that the invention is not limited 30 to the use of pyroxylin composition but embraces other materials which are equivalent in respect to being capable of being readily softened by solvents or heat to a condition in which the fasteners can be so deformed as to provide a secure attachment of the heel to a shoe.

The attachment of my improved heel to a shoe is illustrated in Fig. 2 in which 16 indicates the insole, 18 the insole reinforcement, 20 the outer sole, and 22 the counter portion of the shoe. The 40 heel seat of the shoe is perforated with openings 24, corresponding in number and arrangement with the fasteners 12 projecting from the attaching face of the heel 10, each opening 24 preferably being somewhat larger than the fastener which 45 is to be passed through it, in order to provide for slight adjustments that may be necessary in positioning the heel accurately upon the shoe. The only special preparation required to prepare the shoe for the reception of the heel consists in 50 punching these openings.

The operation of attaching the heel to the shoe is simple, consisting in passing the ends of the fasteners 12 through the holes 24, pressing the heel tightly upon the heel seat of the shoe, softening 55 the ends of the fasteners, either with a solvent or with heat, and flattening down the softened portions to fill the holes 24 and preferably bending over and flattening down the points of the fasteners as shown at 26. When the 60 fastener material has again hardened the attachment of the heel is complete and is exceptionally secure. It will be observed that the practice of my improved method permits the fasteners to be positioned closer to the rim of the heel than is 65 practicable with the heel attaching nails which are commonly used, even though the nails be driven from the inside of the shoe, and consequently a very tight edge joint is secured between the heel and the shoe and is permanently maintained, since there is no possibility of the fasteners loosening, as sometimes occurs with nails.

In Fig. 3 is illustrated a heel which is built up in the conventional manner of separate lifts 28. In this case the fasteners 12 may be inserted during 70 the heel assembling operation through holes

formed in a sufficient number of the heel lifts to insure that the fasteners will be held securely in the heel, the heads 14 of the fasteners being positioned at the joints between the lifts.

Figs. 4 and 5 illustrate a modified form of heel 5 in which certain of the fasteners, as shown at 30, pass all the way through the heel, preferably being inserted through previously drilled holes which are counterbored at the tread face of the heel sufficiently to accommodate collars 32 upon 10 the fasteners 30. In this case the fasteners 30 are provided with short projecting portions 34 designed to receive and hold a toplift 36 provided with holes 38. In order to insure secure attachment of the 15 toplift, an adhesive, such, for example, as pyroxylin cement, may be applied to the projections 34 or in the holes 38 before the top lift is pressed upon the heel. In Fig. 4 there is also shown a short fastener 40 secured by cement in the extreme 20 rear portion of the heel in order to provide for a tight attachment of the heel at the back of the shoe.

In the modification shown in Fig. 6, holes are drilled through the attaching face to a sufficient depth in the heel, which may be of wood or the 25 like, the said holes preferably being screw threaded or otherwise undercut, as shown at 42. The fasteners in this modification consist of short celluloid rods 44 forced into pyroxylin solution or cement introduced into the holes in the heel, a 30 suitable length of each rod being left projecting from the attaching face of the heel.

While a number of specific embodiments of the invention have been illustrated and described in detail, it should be understood that these are 35 merely illustrative and that it is within the scope of the invention to provide still other arrangements of parts employing the same principles.

Having described the invention, what is claimed as new and desired to be secured by Letters Pat- 40 ent is:

1. As an article of manufacture, an unattached shoe heel which has permanently embedded therein and projecting therefrom a fastener which is capable of being readily softened to a 45 condition of easy deformability.

2. As an article of manufacture, a one piece composition heel having molded therein and projecting from the attaching face thereof a plurality of fasteners capable of being readily softened 50 to a condition of easy deformability.

3. As an article of manufacture, an unattached shoe heel consisting of a composition containing wood in which are permanently molded attaching fasteners which project from the attaching face 55 of the heel and are capable of being readily softened by a solvent to a condition of easy deformability.

4. As an article of manufacture, an unattached shoe heel loaded with pyroxylin fasteners which 60 project from the attaching face of the heel.

5. As an article of manufacture, an unattached shoe heel loaded with stiff, thermoplastic fasteners which project from the attaching face of 65 the heel.

6. The method of attaching a heel to a shoe which comprises loading a heel with a plurality of stiff fasteners capable of being readily softened to a condition of easy deformability, leaving the ends of the fasteners projecting from the 70 attaching face of the heel, making a plurality of holes through the heel seat of a shoe, passing the ends of said fasteners through the holes and pressing the heel upon the heel seat, softening the ends of the fasteners, and flattening said sof- 75

tened ends upon the inner face of the insole of the shoe.

7. The method of attaching a heel to a shoe which comprises loading a heel with a plurality of stiff pyroxylin fasteners projecting from the attaching face thereof, making a plurality of holes through the heel seat of a shoe, passing the ends of

said fasteners through the holes and pressing the heel upon the heel seat, softening the ends of the fasteners, bending them outward upon the insole toward the edge thereof, and permitting them to harden.
